UNITED STATES PATENT OFFICE.

HENRY R. HOLTON, OF CHICAGO, ILLINOIS.

ELECTRICAL RELAY.

1,235,978.

Specification of Letters Patent.

Patented Aug. 7, 1917.

Application filed October 23, 1916. Serial No. 127,239.

To all whom it may concern:

Be it known that I, HENRY R. HOLTON, a citizen of the United States, residing at Chicago, in the county of Cook and State 5 of Illinois, have invented certain new and useful Improvements in Electrical Relays, of which the following is a specification.

This invention relates to an improved electrical relay and has as its primary object 10 to provide a device of this character especially designed for use in connection with electric clock systems, telephone systems, program systems and the like and designed for closing, by means of a master regulator, 15 any reasonable number of circuits in multiple, thus eliminating the necessity for the use of a separate relay for each circuit as well as a master relay for the regulator.

The invention has as a further object to 20 provide a device of this character employing a plurality of spring contacts engageable by a contact member for closing a circuit through all of said contacts and to further provide an improved mounting for 25 the said contacts.

The invention has as a further object to 30 provide an improved mounting for the electro-magnet employed and wherein the armature of the said magnet will be provided with a strike plate to prevent the said armature from sticking so that the armature may move to swing the contact member for a quick make and break between the said member and the said spring contacts.

35 And the invention has as a still further object to provide a relay which will be of rugged character and so constructed that any of the parts liable to be affected by wear may easily be removed as occasion may demand.

Other and incidental objects will appear as the description proceeds and in the drawings wherein I have illustrated the preferred embodiment of the invention and wherein 45 similar reference characters designate corresponding parts throughout the several views:

Figure 1 is a plan view of my improved device particularly showing the arrangement of the spring contacts employed and the mounting of the stop guard for limiting the outward throw of the armature,

Fig. 2 is a bottom plan view more particularly illustrating the manner in which 55 the insulating plate of the base is connected to the supporting frame therefor as well as

the mounting of the electrical terminals of the device,

Fig. 3 is a longitudinal sectional view more particularly showing the mounting of 60 the spring contacts as well as the mounting of the armature of the electro-magnet.

Fig. 4 is a sectional view taken on the line 4-4 of Fig. 3 and particularly showing the mounting of the electro-magnet, 65

Fig. 5 is a sectional view taken on the line 5-5 of Fig. 3 and particularly showing the supporting bars for the spring contacts and the insulating strips between the said bars,

Fig. 6 is a detail perspective view of the armature, this view particularly showing the strike plate carried by the armature for preventing the sticking of the armature, and 70

Fig. 7 is a detail perspective view showing 75 one of the insulating strips employed between the supporting bars for the spring contacts.

In carrying out the invention, my improved relay is formed with a base including a preferably oblong metallic supporting frame 10 upon which is mounted an insulating plate 11. The frame 10, at its extremities, is provided with apertured ears 12 for connecting the base with a suitable supporting structure and projecting inwardly from the sides and ends of the frame at the upper margins thereof are, as particularly shown in Fig. 2, a plurality of lugs 13 receiving screws or other suitable 80 fastening devices connecting the plate 11 with the frame.

Mounted upon the plate 11 adjacent one extremity of the base is a transversely arranged electro-magnet 14. This magnet is 95 formed with a suitable core 15 reduced at its extremities to provide trunnions 16. The trunnions 16 are removably fitted through metallic pole blocks 17 with screws or other suitable fastening devices 18 threaded into 100 the ends of the said trunnions for detachably connecting the electro-magnet with the said blocks. The blocks 18 are seated upon the plate 11 adjacent opposite side edges thereof and are detachably connected with 105 the said plate by a cross strip 19. This strip is preferably formed of spring brass and at its ends is provided with reduced terminals removably fitted through suitable openings in the blocks 18 with the said strip spaced 110 slightly above the plate 11. Inserted through this plate from the lower side there-

of are attaching screws or other suitable fastening devices 19' engaging opposite extremities of the strip 19 for securing the said blocks upon the plate. Fitted through the plate 11 to engage the strip 19 substantially midway the ends thereof is a locking screw or other suitable fastening device 19'' adjustable for bowing the said strip downwardly to consequently lock the screws 19' 10 in engagement therewith and thereby also lock the blocks 18 upon the plate 11. In this connection, it is to be observed that the blocks 17 may be easily displaced for removing the magnet 14 and accordingly, magnets of different resistance may be readily used in connection with the device and substituted one for the other to meet the varying requirements in the field of use of the device. The terminals of the 20 winding of the magnet 14 are, as particularly shown in Fig. 2, carried through the plate 11 and connected to binding posts 20 mounted at opposite sides of the said plate in front of the electro-magnet. Arranged to operate with the pole blocks 17 is an armature 21 of iron or other suitable material. Connected to the lower extremity of this armature is a pivot bar 22 received between the pole blocks 17 and formed at its extremities 30 with trunnions 23 fitted through the said blocks for pivotally supporting the armature. The bar 22 is formed of brass or other non-magnetic material and is secured to the armature by pins or other approved fastenings and if desired, suitable non-magnetic washers, as particularly shown in Figs. 1 and 6, or a liner of similar material, may be interposed between the said bar and the armature. As shown in Fig. 3, the armature 40 21 is mounted to normally gravitate away from the blocks 17 and is movable upon the trunnions 23 to engage at its ends with the said blocks. Mounted upon the inner face of the armature is a resilient strike plate 24 preferably formed from a suitable piece of non-magnetic material such as copper. The plate 24 is connected at a point intermediate its ends to the armature 21 by a screw or other suitable fastening device 25 with the 50 ends of the plate normally deflected away from the ends of the armature. Accordingly, it will be seen that when the armature is moved to engage the blocks 17, the extremities of the plate 24 will be compressed between the armature and the said blocks with the plate yieldably acting to spring the armature away from the said blocks so that upon the deenergization of the electro-magnet, the armature will be quickly freed. Any possibility of the sticking of the armature is thus overcome. Furthermore, the provision of the plate 24 will materially enhance the decisive movement of the armature.

55 Connected to the upper ends of the blocks

17 to extend transversely therebetween is a stop guard 26 which, at a point substantially midway its ends is provided with a laterally projecting hook 27 engaging over the upper edge of the armature 21 for limiting the armature in its movement away from the said blocks. This guard will prevent undue displacement of the armature with respect to the blocks.

Mounted upon the outer side of the armature 21 is an angular contact member 28 of suitable metal, one arm of which is connected to the lower extremity of the armature by screws or other suitable fastening devices while the other arm 29 of the said contact member extends laterally away from the armature and is provided at its outer extremity with an upstanding flange or rib 30. Mounted upon this rib to extend from end to end thereof, is a contact strip 31 of silver, tungsten, or other approved material. The contact member 28 is of a length substantially equal to that of the armature 21 and it will now be observed that the stop guard 26 is arranged to engage the upper edge of the armature for limiting the armature in its outward movement with the arm 29 of the contact member resting upon the plate 11 of the base. The said arm will thus be relieved of any strain. If desired, the contact member may be insulated from the armature. Connected with the contact member 28 at a point substantially midway the ends thereof, is an electrical conductor 32 preferably of the ribbon type. This conductor is secured to the contact member by a screw or other suitable fastening device threaded into the armature 21 with the said conductor extending freely through an opening 33 in the arm 29 of the contact member and thence through a suitable opening in the plate 11 of the base to be secured to a binding post 34 upon the said plate. As shown in Fig. 1, the post 34 is preferably arranged between the posts 20.

105 Mounted upon the extremity of the base opposite the electro-magnet 14 are a plurality of longitudinally extending contact supporting bars 35. These bars are preferably formed of brass or phosphor bronze and are arranged in substantially parallel relation upon the plate 11 of the base to be secured thereto by screws or other suitable fastening devices 36 inserted through the bottom of the plate 11 to engage the said 110 bars adjacent opposite extremities thereof. Separating the bars 35 are a plurality of insulating strips 37 of fiber or similar material. Each strip, adjacent the outer extremity thereof, is formed with an upstanding 115 extension 38 and at its lower edge is provided at opposite sides thereof with longitudinally extending flanges 39. As will be observed upon reference to Fig. 5, the lower edges of the bars 35 are inwardly cut or 120 125 130

beveled to provide shoulders 40 and the flanges 39 of the strips 37 are arranged to engage beneath these shoulders with the bars 35 thus acting to hold the said strips against warping. Arranged upon the bars 35 to extend longitudinally thereof, are a plurality of spring contacts 41 having their outer extremities received between the upstanding extensions 38 of the strips 37 and connected with the bars 35 by screws or other suitable fastening devices 42. In this connection, it is to be observed that the strips 37, throughout the major portion of their length terminate flush with the upper faces of the bars 35 with the extensions 38 of the said strips extending above the said bars at the outer ends thereof. The outer extremities of the contacts 41 fit snugly between the said extensions so that should one of the two screws connecting each of the said contacts with its supporting bar become displaced, the adjacent extensions 38 of the said strips will engage the said contact to prevent the contact from pivoting upon the other screw 25 to engage with any of the other contact strips.

In employing the bars 35, a rigid and secure mounting is provided for the contacts 41. Furthermore, these bars are arranged 30 to space the contacts from the insulating plate 11 so that the said plate, as is often times the case, will not chemically act upon the said contacts to cause their corrosion or discoloration. As particularly shown in Fig. 3, the bars 35 are provided with beveled or inclined upper faces 43 sloping toward the inner ends of the said bars so that the inner extremities of the contacts 41 are normally spaced a slight distance from the 35 said bars. Free movement of the inner extremities of the contacts is thus permitted and these contacts are arranged to project over the inner ends of the bars 35 to coöperate with the contact member 28. Preferably, 40 each of the said contacts is formed with a contact point 44 of silver, tungsten or the like, with the said contact point confronting the contact strip 31.

It will now be seen that when the armature is attracted by the electro-magnet, the contact member 28 will be moved to simultaneously close a circuit through all of the contacts 41 with the inner ends of the said contacts adapted to flex with respect to the inclined faces 43 of the bars 35 to seat against the contact strip 31 of the said contact member. Furthermore, it will be observed that the armature is so mounted that a quick make and break will be had between 50 the contact member and the said contacts. Connected to the outer extremities of the bars 35 are binding screws 45 for receiving the circuit wires from the contacts 41, and it will be noted that the extensions 38 of the 55 strips 37 are arranged to insulate the upper

extremities of these screws with respect to each other so that the free ends of the said wires will not accidentally be brought into contact when connected with the said screws.

I thus provide an exceedingly simple and efficient construction for the purpose set forth and a relay adapted to be associated with a master regulator for simultaneously closing a plurality of circuits of a system in multiple to dispense with the use of an individual relay for each circuit. Furthermore, the several parts of the device are so mounted that each part subjected to wear may be easily observed and removed as occasion may demand.

Having thus described the invention, what is claimed as new is:

1. An electrical relay including a base, an electro-magnet mounted thereon, an armature mounted to coöperate with the said magnet, a contact member carried by the said armature to swing therewith, an elongated supporting block mounted upon the base, and a spring contact connected to the upper face of said block and arranged to 85 coöperate with said contact member with the block extending beneath the contact throughout the major portion of the length thereof.

2. An electrical relay including a base, upstanding pole blocks carried thereby, an electro-magnet mounted upon the said blocks, an armature arranged to coöperate with the magnet and shiftable to engage said blocks, a yieldable strike plate connected intermediate of its ends to the armature 95 with the extremities of the said plate deflected away from the armature to engage the inner vertical edges of said blocks to prevent sticking of the armature, a contact member carried by the armature, and a contact mounted upon the base to coöperate with the said contact member.

3. An electrical relay including a base, an electro-magnet mounted thereon, pole blocks upstanding from the base and supporting 100 the said magnet to extend transversely therebetween, an armature swingingly connected with said block to coöperate with the magnet and movable to abut the inner vertical edges of the blocks, a contact mounted upon 105 the base, and an angular contact member having one arm thereof connected to the lower extremity of the said armature with the other arm of the contact member extending beneath the said contact to coöperate 110 therewith.

4. An electrical relay including a base, an electro-magnet mounted thereon, pole blocks supporting the said magnet, an armature swingingly connected with said blocks to co- 115 operate with the magnet, a stop guard connecting the said blocks and arranged for engagement with the free extremity of the armature for limiting the armature in its outward throw away from the magnet, a 120

- contact member carried by the armature, and a spring contact mounted upon the base to coöperate with the said contact member.
5. An electrical relay including a base, an electro-magnet mounted thereon, a swingingly mounted armature arranged to coöperate with the magnet, a contact member connected to the said armature to swing therewith, a metallic supporting block 10 mounted upon the base and provided with a beveled upper face, and a spring contact connected to the upper face of said block with the free extremity of said contact extending away from the beveled face of the 15 block to coöperate with the said contact member.
6. An electrical relay including a base, an electro-magnet mounted thereon, an armature arranged to coöperate with the magnet, 20 a contact member carried by the said armature to swing therewith, a plurality of supporting blocks mounted upon the base, insulating strips between the said blocks, and a plurality of spring contacts connected with 25 the blocks to project over the inner ends thereof for coöoperating with the said contact member.
7. An electrical relay including a base, an electro-magnet mounted thereon, an armature arranged to coöperate with the magnet, 30 a contact member carried by said armature, a plurality of supporting blocks mounted upon the base and provided with shoulders at their lower margins, insulating strips between the said blocks and provided with flanges engaging with said shoulders, and a plurality of spring contacts mounted upon 35 the said blocks with the said contacts projecting over the inner extremities of the blocks to coöperate with the said contact member.
8. An electrical relay including a base, an electro-magnet mounted thereon, an armature arranged to coöperate with the magnet, 40 a contact member carried by said armature, a plurality of supporting blocks mounted upon the base, insulating strips between the said blocks and provided at their outer extremities with upstanding extensions projecting above the blocks, and a plurality of 45 spring contacts having their outer extremities fitted between the said extensions and secured to the blocks with the inner extremities of said contacts projecting over the inner ends of the blocks to coöperate with the said contact member.
9. An electrical relay including a base, an electro-magnet mounted thereon, an armature arranged to coöperate with the 50 magnet, a contact mounted upon the base, an angular contact member having one arm thereof secured to the armature with the other arm of the said member arranged to coöperate with the said contact, and a conductor connected with said first mentioned 55 arm of the contact member and loosely received through the other arm thereof.
10. An electrical relay including a base, an electro-magnet mounted thereon, pole blocks supporting the magnet, and means extending between the blocks, means connected with the base and engaged with said first mentioned means for securing the blocks upon the base, an armature arranged to coöperate with the magnet, a contact member carried by the armature and a contact mounted upon the base to coöperate with the said member. 70
11. An electrical relay including a base, an electro-magnet mounted thereon, pole blocks supporting the magnet, a strip extending between the said blocks, means connected with the base and adjustably engaged with said strip for securing the blocks upon the base, an armature arranged to coöperate with the magnet, a contact member carried by the armature, and a contact mounted upon the base to coöperate with the said member. 75
12. An electrical relay including a base, an electro-magnet mounted thereon, pole blocks supporting the magnet, means extending between the said blocks, means connected with the base and engaged with the said first mentioned means for securing the blocks upon the base, means connected with the base and engaged with said first mentioned means for locking the said second mentioned means in engagement with the said first mentioned means, an armature arranged to coöperate with the magnet, a contact member carried by the said armature, and a contact mounted upon the base to coöperate with the said member. 80
13. An electrical relay including a base, an electro-magnet mounted thereon, pole blocks supporting the magnet, a strip extending between the said blocks, means connected with the base and engaged with said strip for securing the blocks upon the base, means connected with the base and adjustably engaged with the strip for locking the said first mentioned means in engagement with the strip, an armature arranged to coöperate with the magnet, a contact member carried by the armature, and a contact mounted upon the base to coöperate with the said member. 85
14. An electrical relay including a base, an electro-magnet mounted thereon, pole blocks supporting the magnet upon the base, an armature, a pivot bar connected to the armature to extend longitudinally thereof and reduced at its extremities to provide trunnions engaged with said blocks for 90 swingingly supporting the armature to coöperate with the said magnet, a contact member carried by the armature, and a contact mounted upon the base to coöperate with the said member. 95
15. An electrical relay including a base, an electro-magnet mounted thereon, pole blocks supporting the magnet upon the base, an armature, a pivot bar connected to the armature to extend longitudinally thereof and reduced at its extremities to provide trunnions engaged with said blocks for 100 swingingly supporting the armature to coöperate with the said magnet, a contact member carried by the armature, and a contact mounted upon the base to coöperate with the said member. 105
16. An electrical relay including a base, an electro-magnet mounted thereon, pole blocks supporting the magnet upon the base, an armature, a pivot bar connected to the armature to extend longitudinally thereof and reduced at its extremities to provide trunnions engaged with said blocks for 110 swingingly supporting the armature to coöperate with the said magnet, a contact member carried by the armature, and a contact mounted upon the base to coöperate with the said member. 115
17. An electrical relay including a base, an electro-magnet mounted thereon, pole blocks supporting the magnet upon the base, an armature, a pivot bar connected to the armature to extend longitudinally thereof and reduced at its extremities to provide trunnions engaged with said blocks for 120 swingingly supporting the armature to coöperate with the said magnet, a contact member carried by the armature, and a contact mounted upon the base to coöperate with the said member. 125
18. An electrical relay including a base, an electro-magnet mounted thereon, pole blocks supporting the magnet upon the base, an armature, a pivot bar connected to the armature to extend longitudinally thereof and reduced at its extremities to provide trunnions engaged with said blocks for 130 swingingly supporting the armature to coöperate with the said magnet, a contact member carried by the armature, and a contact mounted upon the base to coöperate with the said member.

15. An electrical relay including a base, an electro-magnet mounted thereon and including a core formed with terminal reduced portions, pole blocks supporting the 5 magnet upon the base and having the said reduced portions of the core of the magnet fitted therethrough, means engaged with the extensions of the magnet core and connect-

ing the magnet with the said blocks, an armature mounted to coöperate with the magnet, a contact member carried by the armature, and a contact mounted upon the base to coöperate with the said member. 10

In testimony whereof I affix my signature.

HENRY R. HOLTON. [L. S.]
